UNITED STATES PATENT OFFICE

160,549

AUTOMOBILE RADIATOR GRILLE BAR

Edward O. Sheard, Detroit, Mich., assignor to Chrysler Corporation, Highland Park, Mich., a corporation of Delaware

Application August 13, 1949, Serial No. 4,456

Term of patent 7 years

(Cl. D14—18)

To all whom it may concern:

Be it known that I, Edward O. Sheard, a citizen of the United States, residing in the city of Detroit, county of Wayne, and State of Michigan, have invented a new, original, and ornamental Design for an Automobile Radiator Grille Bar, of which the following is a specification, reference being had to the accompanying drawing, forming part thereof, in which:

Fig. 1 is a top plan view of my novel grille bar;
Fig. 2 is a front elevation thereof; and

Figs. 3 and 4 are sections taken on the lines
3—3 and 4—4 of Fig. 2.

The dominant features of my design are shown in solid lines.

I claim:

The ornamental design for an automobile radiator grille bar, substantially as shown and described.

EDWARD O. SHEARD.
